WATER COOLED GENERATOR SPRAY NOZZLE

Filed Nov. 15, 1949

FIG. 2.

FIG. 1.

UNITED STATES PATENT OFFICE

2,561,038

WATER-COOLED GENERATOR SPRAY
NOZZLEPercy L. Symons, Portland, Oreg., assignor to
Albina Engine & Machine Works, Inc., a cor-
poration

Application November 15, 1949, Serial No. 127,450

2 Claims. (Cl. 299—144)

1

This invention relates generally to the art of making gas from fuel oils and particularly to a water cooled generator spray nozzle.

The main object of this invention is to produce a water cooled tip wherewith oil can be sprayed into a cracking tower in which the spraying tip is subjected to relatively high temperatures.

The second object is to construct a spray nozzle which will be easy to fabricate and which is made up of steel tubing and cast sections united by a welding process.

These and other objects are accomplished in the manner set forth in the following specifications as illustrated in the accompanying drawings, in which:

Fig. 1 is a longitudinal section taken along the line 1—1 in Fig. 2, through a tip showing it mounted on an oil pressure pipe and its cooling water connections.

Fig. 2 is a section along the line 2—2 in Fig. 1.

Fig. 3 is a section along the line 3—3 in Fig. 1.

Fig. 4 is a fragmentary perspective view of the nozzle with parts broken away in section.

Like numbers of reference refer to the same or similar parts throughout the several views.

Referring in detail to the drawing, there is shown an internal steam pipe 10 to which high pressure steam is supplied from a source not shown. Threaded on the pipe 10 is a tubular core 11 having three short radial centering ribs 12, 13 and 14 formed along the discharge end thereof and a circular flange 15 forming the inlet end of the nozzle. There are also formed along the core 11, the radial ribs 16 which extend outside the surface 17 of the flange 15.

A steel shell 18 is wrapped around the core 11 and rests upon the flange 15 and the short ribs 12, 13 and 14 and it is secured to the ribs 16 and flange 15.

A separate curved plate 19 covers the space 20 between the ribs 16, to which cold water is admitted from a pipe 21 through the hole 22.

The space 23 around the core 11 on both sides of the space 20 communicates through the duct 24 with the space 23 through which the heated water escapes through the hole 25 into which is threaded the hot water return pipe 26.

The end 27 is inclined somewhat with relation to the axis of the nozzle.

It will be noted that the shell 18 and curved plate 19 extend to the welds 28 at the cast head portion 29. A circular row of outlet ports 30 connect the chamber 31 with the exterior of the nozzle through the end 27.

2

Extending from the steam pipe 10 is an oil supply pipe 32 whose enlarged end 33 is provided with holes 34 through which steam passes from the pipe 10, through the space 35 into the chamber 31. The end 33 is threaded into the portion 36 of the core 11.

No attempt is made to show the details of the cracking chambers and piping for oil, water and steam, as their use is well understood.

10 Attention is drawn to the fact that all of the cooling water entering the nozzle through the pipe 21 must pass through the end 27 which projects into the retort and is subjected to the greatest heat.

15 After the water has absorbed its heat from the small end zone, it spreads out around the space 23 and makes it way more leisurely to the outlet pipe 26.

20 It can be seen that by combining the cast and wrought sections, it is possible to construct a form of nozzle especially adapted for use under the severe conditions found in gas cracking equipment.

25 In practice the nozzle projects horizontally into a cracking tower lined with refractory material with only the inclined cast portion of the nozzle extending into the zone of greatest heat.

I claim:

30 1. A generator spray nozzle consisting of a cast cylindrical core having an outwardly flanged end, and having a pair of radial ribs joined to said flanged end, a wrought steel shell secured around said core and spaced therefrom forming two unequal separated water jackets around said core, one of said ends having a duct therethrough connecting said jackets, said duct containing end having a plurality of outlet spray forming ports communicating with the interior of the nozzle, a high pressure steam pipe threaded into the 35 opposite flanged end, an oil pipe within said steam pipe and a vaporizing tip on said oil pipe threaded into the outlet end of said nozzle and spaced from said outlet ports.

40 2. A spray nozzle comprising a tubular cast core having an outwardly flanged open end and having a closing head formed at the other end exceeding the diameter of said core, said head having its extreme end inclined with relation to the axis of the core, said head having a duct 45 formed along its inclined end so that the duct is also inclined with relation to the core axis and having its inlet and outlet ends arcuate in form and disposed close to said core, said closed end having a chamber formed therein having 50 outlet ports therein on opposite sides of said duct,

a tubular shell surrounding said core and spaced therefrom by said flange, said core having a pair of radial ribs extending from said flange to said head on opposite sides of the duct inlet and forming thereby a cold water inlet duct while the balance of the space between said core and shell forms a water return duct, a steam pipe connected to the outwardly flanged end, and oil pipe within said steam pipe spaced therefrom and connected with said chamber, the end of said oil pipe having holes therein communicating with said steam pipe.

PERCY L. SYMONS.
